Richard Wareham, Euclid, and Ralph Ellsworth, Wiloughby, Ohio, assignors to Superior Funeral Supply Corporation, Cleveland, Ohio, a corporation of Ohio

Filed Jan. 4, 1966, Ser. No. 446

Term of patent 14 years

(Cl. D48—20)

The single figure is a perspective view of a floor lamp base embodying our new design, the opposite sides not shown, being substantially mirror images of the sides shown.

The dominant features of our design reside in the portions shown in full lines.

We claim:

The ornamental design for a floor lamp base, as shown and described.
